UNITED STATES PATENT OFFICE

2,549,529

MAGNETIC CHIP COLLECTOR FOR
GRINDERS

Alfred V. Sandlin, Corpus Christi, Tex.

Application November 10, 1947, Serial No. 785,105

2 Claims. (Cl. 51—270)

1

This invention relates to new and useful improvements and structural refinements in electric grinders, and the principal object of the invention is to provide an attachment for such grinders in the form of what may be referred to as a magnetic chip collector, whereby particles of iron and steel which usually fly from the grinder wheel will be forcibly prevented from flying loosely and possibly injuring the operator.

A further object of the invention is to provide a chip collector for grinders even through they are equipped with so-called safety guards, since it is well-known that such guards do not fully deflect all the particles or chips which emanate from the grinder wheel.

Another object of the invention is to provide a magnetic chip collector which is simple in construction and which may be quickly and easily attached to grinders of various types and sizes.

An additional object of the invention is to provide a magnetic chip collector for grinders which will readily lend itself to economical manufacture, and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a front elevational view of a grinder showing the invention in situ thereon.

Figure 2 is a top plan view of the subject shown in Figure 1, the same being partially broken away to reveal the invention, and

Figure 3 is a cross-sectional view, taken substantially in the plane of the line 3—3 of Figure 1.

Like characters of reference are used to designate like parts in the specification and throughout the several views.

Referring now to the accompanying drawings in detail, the general reference character 10 designates a grinder of conventional design, which embodies in its construction a suitable electric motor 11 mounted upon a base 12, the armature 13 of the motor carrying a grinding wheel 14, as will be clearly apparent.

The wheel 14 is partially enclosed by means of a safety guard 15 which, in many instances, is associated with the motor 11 through the medium of the connecting sleeve 16, and the essence of novelty in the invention resides in the provision of a magnetic chip collector designated

2

generally by the reference character 17, which will be presently described.

The chip collector 17 embodies in its construction an arcuate member or trough 18 having a V-shaped cross-sectional configuration as shown in Figure 2, the member 18 being provided at one end with a bracket 19 whereby it is secured to one end of an arcuate electro-magnetic coil 20.

The entire collector 17 is disposed within the guard 15 to which it is secured by means of a suitable bolt or screw 21, matters being so arranged that the arcuate member 18 is disposed adjacent the periphery of the wheel 14, as is best illustrated in Figure 3.

15 The electro-magnetic coil 20 is connected in parallel by means of a twin conductor 22 to a switch 23 which controls the operation of the motor 11, so that the electro-magnetic coil is energized simultaneously with the motor 11 when the grinder is to be used.

As will be clearly apparent, the switch 23 is conveniently mounted within the base 12.

When the invention is placed in use, supply of current is simultaneously delivered to the motor 11 and to the coil 20, resulting in the rotation of the wheel 14 and in simultaneous magnetization of the member 18. Accordingly, when a steel or iron object is being ground on the wheel 14, particles of iron or steel will be attracted by the member 18 and thereby prevented from flying beyond the guard 15 and possibly injuring the operator. After the supply of current to the motor 11 and to the coil 20 is discontinued, the coil as well as the member 18 will become demagnetized, and any particles which have gathered on the member 18 will simply drop downwardly to the floor through an outlet duct 24. This outlet duct may simply assume the form of a pipe or tube secured to the lower portion 20 of the guard 15, as indicated in Figure 3.

Needless to say, when the motor 11 is used in association with tool grinding wheels, two of the collectors 17 and two outlet ducts 24 should be used, as exemplified in the accompanying drawings.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted

to without departing from the spirit and scope of the invention as claimed.

Having described the invention what is claimed as new is:

1. In a grinder, the combination of a rotatable grinding wheel, a sector-shaped guard including spaced side walls and an arcuate edge wall enclosing respective side and peripheric portions of said wheel, and an arcuate magnet secured to the inner surface of the arcuate edge wall of said guard, and an arcuate chip collecting trough carried by said magnet and having magnetizable chip collecting surfaces disposed in V-shaped formation adjacent the periphery of said wheel, whereby metallic chips projected by said grinding wheel into said guard may be attracted by said magnet and collected in said trough. 15 5

2. The device as defined in claim 1 wherein said guard includes a downwardly extending chip outlet duct, said magnet being demagnetizable and being disposed above said duct to gravitationally discharge chips through said duct upon demagnetization of said magnet.

ALFRED V. SANDLIN.
